CLAIM

The ornamental design for a filter housing for a water filtration pitcher, as shown and described.

DESCRIPTION

FIG. 1 is a front top perspective view of the new design.

FIG. 2 is a rear top perspective view of the new design.

FIG. 3 is a front bottom perspective view of the new design.

FIG. 4 is a rear bottom perspective of the new design.

FIG. 5 is a right side view of the new design.

FIG. 6 is a left side view of the new design.

FIG. 7 is a front view of the new design.

FIG. 8 is a rear view of the new design.

FIG. 9 is a top view of the new design; and,

FIG. 10 is a bottom view of the new design.

The broken lines shown in the drawings illustrate portions of the filter housing that form no part of the claimed design. The shading lines shown in the drawings represent the approximate three-dimensional contour of the claimed design and are not intended to indicate surface decoration.
